PARING AND SHELLING TOOL

Clinton S. Hall, Farmington, Mich.

Application August 14, 1947, Serial No. 768,613

4 Claims. (Cl. 130—30)

1

The present invention relates to improvement in a food paring tool which is particularly adapted for paring fruit and vegetables and for shelling peas, beans, and the like.

Primary objects of the present invention are:

(1) To provide a simplified and economically manufactured paring tool of improved construction which is adapted to utilize a conventional double edged razor for the cutting element, and which provides a simplified curling element to curl parings out of the operator's way;

(2) To provide an improved paring head for such a tool which may be readily and quickly mounted selectively to a handle in one of two alternative positions to effect different paring depths, and to provide an improved clasp for simplifying the mounting of said paring head to its handle;

(3) To provide a paring tool having a pivotally mounted paring head adapted to ride with the contour of the object being pared so as to cut at a uniform paring depth, thereby reducing waste and facilitating the paring operation;

(4) To provide a paring tool of the character described which may be conveniently used in either the left or right hand of the operator; and

(5) To provide a novel and improved paring tool which is particularly adapted for use in shelling peas, beans, and the like.

Other objects of this invention will appear in the following description and appended claims, reference being had to the accompanying drawings forming a part of this specification wherein like reference characters designate corresponding parts in the several views.

In the drawings:

Fig. 1 is a top view of a paring tool embodying the present invention.

Fig. 2 is essentially a side view of the tool shown in Fig. 1, showing the pivotal paring head in an alternative position in phantom.

Fig. 3 is a fragmentary enlarged vertical section through the paring head and taken essentially in the direction of the arrows along the line 3—3 of Fig. 1, showing a potato in phantom being peeled.

Fig. 4 is essentially a fragmentary bottom view of the paring end of the tool shown in Figs. 1 and 2.

Fig. 5 is essentially an oblique view of another embodiment of a paring tool employing the present invention.

Fig. 6 is an enlarged vertical section taken substantially in the direction of the arrows along the line 6—6 of Fig. 5, showing a pod of peas in phantom being shelled.

2

Fig. 7 is essentially a fragmentary view of the end portion of the stripper finger, taken in the direction of the arrows along the line 7—7 of Fig. 6.

Fig. 8 is essentially a section through the stripper finger, taken in the direction of the arrows along the line 8—8 of Fig. 6.

Before explaining the present invention in detail, it is to be understood that the invention is not limited in its application to the details of construction and arrangement of parts illustrated in the accompanying drawings, since the invention is capable of other embodiments and of being practiced or carried out in various ways.

Also it is to be understood that the phraseology or terminology employed herein is for the purpose of description and not of limitation.

Referring to the drawings, a particular embodiment of the present invention is shown in

20 Figs. 1 through 4 wherein a handle member 10, which may be suitably formed from a sheet metal stamping, molded plastic, or the like, provides the lateral paring head holding arms 12 and 14. The arm 12 provides the pivot hole 16, Fig. 3. The arm 14 provides the corresponding pivot slot 18, Fig. 2. A movement limiting stop 20 projects inward from the arm 12 to limit the pivotal movement of the arcuate blade holding seat 22, which latter is essentially symmetrically constructed on 30 opposite sides of the longitudinally extending groove 24, Figs. 1 and 3.

Parallel to the groove 24 and on opposite sides thereof are the two longitudinal paring slots 26, each having a mesial chamfered edge 28 and being bounded laterally by a guide bar 30 integral

35 with the blade seat 22 and being connected therewith by the arm portions thereof which determine the short end boundaries of the longitudinal paring slots 26. With the paring head in the operative position shown in Fig. 3, the internal edge of each guide bar 30 is curved upward to provide a rounded contact surface for readily gliding over the surface of the object being pared.

The paring head is detachably connected pivotally in one of two alternative positions between the arms 12 and 14 by means of the two pair of coaxial pivot pins 32 projecting laterally from the blade seat of the paring head and having their longitudinal axes parallel to the guide bars 30.

50 Each coaxial pair of pivot pins 32 is disposed essentially along a continuation of the longitudinal median line of one of each of the longitudinal paring slots 26. One pin 32 of each coaxial pair fits within the pivot hole 16 provided therefor by the arm 12 and the opposite coaxial pin is slidably moved into position within the pivot slot 18

provided therefor in the arm 14 and is suitably held in place by a clasp described in detail below.

The under or convex blade seating surface of the blade seat 22 is adapted to seat a thin double edged blade 34, which preferably may be a conventional double edged razor blade, with one of each of the cutting edges thereof parallel to the guide bars 30 and disposed essentially centrally below one of each of the longitudinal paring slots 26. Thus each cutting edge of the blade 34 is exposed by the corresponding paring slot 26 to permit paring as the paring head is drawn over the surface of an object to be pared. With the razor blade 34 in the operative position shown, the longitudinal median line thereof lies essentially over the longitudinal groove 24 and is held in the operative position shown by the clamping plate 36 which provides the longitudinal ridge 38 adapted to pass through the conventional central opening of the double edged safety razor blade 34 and to fit within the groove 24. The blade 34 is thus detachably clamped securely between the concave surface of the plate 36 and the convex surface of the seat 22 by the plurality of screws 40 within mating screw-threaded holes provided therefor by the groove 24 and ridge 38.

It is preferred that the longitudinal edges 42 of the clamping plate 36 are chamfered as shown in Fig. 3 and are disposed relative to the cutting edges of the blade 34 to leave an exposed portion of each blade below its respective paring slot 26, Fig. 4. The clamping plate 36 also provides the corner wings 44 which cover the corner portions of the thin blade 34 and lend support thereto when the tool is in use.

With the paring head detachably connected pivotally in the operative position shown, the blade 34 being clamped to the convex undersurface of the seat 22 and one coaxial pair of pins 32 being inserted into the corresponding pivot hole 16 and slot 18, the paring head may be conveniently locked in position by the flat hook or clasp 46 which lies parallel to the bracket arm 14 and provides the pin slot 48 adapted to receive the pin 32 within the slot 18 and to cooperate with the slot 18 for completing an enclosure around the said pin 32, Fig. 2. The upper portion of the clasp 46 provides the flange 50 adapted to overlie the upper portion of the arm 14 and to prevent downward pivotal movement of the clasp 46 about the screw 52 which secures the clasp 46 to the arm 14. Upward pivotal movement of the clasp 46 about the screw 52 is prevented by the pin 32, within the slot 18 which pin 32 is held against upward movement by the body of the arm 14. Thus the pin 32 is supported from above and below, respectively, by the body of the arm 14 and by the body of the clasp 46.

The present invention may be utilized in peeling fruits and vegetables by drawing the paring head from left to right across the top of the object being pared, Fig. 3. In paring the potato 53, shown in phantom by way of example in Fig. 3, the leading guide bar 30 adjacent the handle 10 rides along the upper surface of the potato 53. The leading edge of the double edged blade 34 will then cut just below the surface of the potato 53. The paring 55, also shown in phantom, will be separated through the leading paring slot 26. The paring 55 is curled upward and out of the way of the operator as it strikes the rounded outer edge of the groove 24, which latter serves as a curler as well as a means for securing the

blade 34 tightly in position. Otherwise the parings 55 would extend directly across the paring head and interfere with the operator's visibility and inconvenience the paring operation. Potato eyes or other spots from the object being pared are conveniently removed by the sharpened gouge 54 at the end of the handle 10.

It is to be observed that the pivotally mounted paring head permits the latter to follow the contour of the object being pared so that the cutting edge of the blade 34 will pare at an essentially uniform depth regardless of ordinary surface irregularities in the object being pared, such as the potato 53. This feature avoids waste and facilitates the paring operation so that the operator may utilize the tool efficiently and speedily with a minimum of experience or practice.

The depth of the paring cut is determined by the width of the slot 26 and the angular disposition of the cutting edge of the blade 34 relative to the seat 22 and the corresponding guide bar 30. Accordingly, it is feasible to adapt one cutting element of the paring head for deep paring and the other for thin paring. The tool is readily assembled for light or deep paring merely upon loosening the screw 52 and selectively inserting the proper pair of coaxial pivot pins 32 within the hole 16 and slot 18 provided therefor.

An important feature of the present invention is to be noted in the disposition of the paring head with its pivoted axes and cutting elements perpendicular to the longitudinal axis of symmetry of the handle 10. By this provision, the single tool may be conveniently utilized by either a left or right handed operator, the paring head being reversible as described above for either operator to permit a choice as to the paring depth.

Another embodiment of the present invention is shown in Figs. 5 through 8 wherein an essentially H-shaped handle 56 is suitably formed from plastic or sheet metal by way of example and provides the four legs 58 having rounded sides so as to fit comfortably within the palm of the hand of the operator. In order to facilitate gripping the body 56 and to prevent the hand from slipping down the sides thereof, the legs 58 are slightly inclined toward each other from bottom to top so that the spacing between the legs 58 at the top of the handle is less than the corresponding spacing at the bottoms thereof.

Extending in a curve from the body 56 and from between the upper legs 58 is the arcuate stripper finger 60 which terminates in the rounded point 62 and provides the laterally extending pod guides 64, Figs. 7 and 8. The pod guides 64 provide the rounded leading edges 66 and are suitably spaced from the tip 62 to permit the latter to reach the bottom of a pod, such as a pea or bean pod, as the pod guides 64 glide along the edges of an opened pod, Fig. 6. Extended essentially vertically from the body 56 and from between the lower legs 58 is the bracket 68 which terminates in a vertically downward extension 70. Parallel vertical paring head bracket arms 72 and 74 extend forward from the right and left sides respectively of the downward extension 70, Fig. 5, and carry a pivotal paring head between them by means of the pivot slot 76 in the arm 72, corresponding in function to the pivot slot 18 in the arm 14, and the pivot hole 78 in the arm 74, corresponding in function to the pivot hole 16 in the arm 12.

The embodiment of the paring head shown in Figs. 5 through 8 is similar in its essential details

to that already described in Figs. 1 through 4 and includes the arcuate blade seat 80 for the double edged blade 34, the central groove 82, the two paring slots 84 on opposite sides of the groove 82, the mesial chamfered edges 86 of the slots 84, the two guide bars 88 or lateral edges of the slots 84, and the two pair of laterally extending pivot pins 90, all of which are similar in arrangement and function to the corresponding above described features, namely, the arcuate blade seat 22, the groove 24 therein, the two paring slots 26, the mesial chamfered edges 28, the guide bars 30, and the pivot pins 32.

The blade 34 is clamped to the seat 80 by means of the arcuate clamping plate 92, Fig. 5, which provides the longitudinal ridge 94 adapted to fit within the central opening of the blade 34 and the groove 82 and to be secured to the seat 80 by the plurality of screws 96 which screw into screw-threaded openings provided therefor by the ridge 94 and groove 82. The clamping plate 92 also provides the opposite chamfered edges 98 as shown and the four corner wings 100 which cover the corners of the blade 34 to support the latter in the operative position against excessive bending during paring.

The clasp 102 provides the notch 104 for receiving the pin 90 within the slot 76 and is adapted to lie adjacent the side of the arm 72 to prevent removal of the pin 90 from the pivot slot 76 similarly in the manner by which the clasp 46 closes the pivot slot 18. The flange 106 on the end of the clasp 102 overlies the forward edge of the bracket arm 72 to prevent counterclockwise pivoting of the clasp 102 about the screw 108 which secures the clasp 102 to the side of the arm 72. Clockwise pivoting of the clasp 102 is prevented by contact with the pin 90 which is blocked against upward movement by the body of the bracket 72.

A structural difference between the paring head shown in Figs. 5 through 8 and that shown in Figs. 1 through 4 is noted in the upraised guide flanges 110 at opposite ends of each paring slot 84. The flanges 110 serve to guide the object being pared, such as the pea pod 112 shown by way of example in phantom, Fig. 6. Another difference has been the elimination of the movement limiting stop 20. The function of the latter is accomplished by the lower edge of the downward projecting bracket 70, which contacts the lower portion of the blade seat 80 to limit its counterclockwise pivoting, and the upper edge of the bracket 70, which limits clockwise pivoting of the blade seat 80 by contacting the upper portion thereof.

The paring tool shown in Figs. 5 through 8 is particularly adapted for shelling peas, beans, and the like. In operation the tool is held in one hand. The pod to be shell is held in the other hand with the concave curvature thereof facing the paring head. The lower cutting edge of the double edged blade 34 is then drawn downward along the concave edge of the pod, from top to bottom, thereby slicing a paring 114 from the inner or concave edge of the pod 112 and opening the latter. As the paring head is drawn down, it is followed by the stripper finger 60 which enters the uppermost portion of the pod 112 so as to spread the latter apart and strip the peas 116 therefrom, Fig. 6. The paring 114 is curled out of the way of the operator by contact with the outer surface of the groove 82. Thus in one operation, the pod 112 is opened by the paring head and the finger 60 strips the peas 116 from the pod

112. Thus the time consuming preparation of Lima beans, peas, and the like is greatly simplified. The rounded edges 66 of the pod guides 64 glide along the concave edges of the opposite halves of the pod 112 and assist the operator both in holding the pod 112 perpendicular to the stripper finger 60 and in preventing the tip 62 from piercing or gouging the inner surface of the pod 112.

10 The embodiment of the present invention shown in Figs. 5 through 8 possesses all the advantages previously described. It may be used with equal feasibility in either hand. The pivotal paring head is adapted to follow the contours of the object being pared. The double cutting elements may be adapted for thin paring by mounting the paring head in one position or for deep paring by reversing the paring head. Ordinary, Lima beans which require a deep cut 20 may be prepared with on cutting element of the paring head and peas which require a relatively thin cut may be prepared upon reversing the paring head. The change-over from deep paring to thin paring, for example, is readily accomplished by virtue of the simplified clasp 102 which may be quickly loosened with a screw driver or knife blade.

I claim:

1. In a paring tool having a thin cutting blade, 30 the combination of a handle having an axis of symmetry and a paring head pivotally connected therewith about a pivot axis perpendicular to said axis of symmetry, said paring head comprising a blade seat having a longitudinal paring slot 35 therein formed by a guide bar parallel to the axis of said pivotal connection and spaced from said seat by lateral arms connecting said guide bar and seat, means to clamp said blade in an operative position to said blade seat with the cutting 40 edge of said blade parallel to said guide bar and exposed by said slot, an extended stripper finger provided by said handle and having a probe at the end thereof spaced from said cutting blade and perpendicular thereto, and vertical guide 45 flanges projecting from opposite ends of said paring slot.

2. In a paring tool having a thin cutting blade, 50 the combination of a handle and a paring head pivotally connected therewith, said handle including a stripper finger extended over said cutting blade and having its longitudinal axis perpendicular to said cutting blade, said paring head comprising a blade seat having a longitudinal paring slot 55 therein formed by a guide bar parallel to the pivot axis of said pivotal connection and spaced from said seat by lateral arms connecting said guide bar and seat, and means to clamp said blade in an operative position to said blade seat with the cutting edge of said blade 60 parallel to said guide bar exposed by said paring slot.

3. The combination in a paring tool as claimed in claim 2 and being further characterized in that said extended stripper finger is adapted to 65 probe a pea or bean pod and provides a pointed tip and lateral guide bars spaced from said tip for gliding along the edges of said pod when said tip is inserted into said pod.

4. In a paring tool, the combination of a par- 70 ing head comprising a blade seat and clamping means for clamping a double edged safety razor blade in an operative position to said blade seat; a pair of longitudinal paring slots in said blade seat and spaced in parallelism on opposite sides 75 of the median line of said blade seat to overlie

the cutting edges of said safety razor blade clamped to said blade seat, each paring slot being completed by one of each of a pair of parallel guide bars spaced from opposite sides of said seat by lateral arms connecting said seat and guide bars; a handle means having an axis of symmetry to permit either right or left handed operation of said tool; and means for selectively securing said paring head pivotally to said handle about alternative pivot axes which are perpendicular to the axis of symmetry of said handle and parallel to said guide bars, which means include two pair of coaxial pivot pins projected laterally from said paring head on opposite ends of said paring slots and parallel to said guide bars, a pair of bracket arms provided by the handle and spaced on opposite sides of the axis of symmetry of said handle and parallel thereto, a pivot hole in one of said arms for selectively

receiving one of said pivot pins, a pivot slot for slideably receiving the coaxial pivot pin at the other end of the paring slot, and clasp means to close said pivot slot and to hold a pivot pin therein against slideable movement.
